UNITED STATES PATENT OFFICE.

WILLIAM S. RAY, OF SAN FRANCISCO, CALIFORNIA.

WIRE-ROPE RAILWAY.

SPECIFICATION forming part of Letters Patent No. 278,044, dated May 22, 1883.

Application filed May 6, 1881. (No model.)

To all whom it may concern:

Be it known that I, WILLIAM S. RAY, of the city and county of San Francisco, State of California, have invented an Improvement in 5 Wire-Rope Railways; and I hereby declare the following to be a full, clear, and exact description thereof.

My invention relates to certain improvements in wire-rope railways; and it consists of a novel construction of the ropeway and of the gripping apparatus by which the car is connected with the rope, whereby the car may be propelled around curves or made to cross other cable-lines without interfering with 10 them. This is effected by the use of an independent moving device, which is placed in the upper part of the cable tube or tunnel where the curve or crossing is to be made, and a mechanism secured to the grip, which will engage with this device when required, the rope or cable being depressed, so as to be entirely 15 out of the way at these points.

Referring to the accompanying drawings for a more complete explanation of my invention, 20 Figure 1 is a perspective view of a curve, showing the relative position of the apparatus. Fig. 2 is a perspective view of a crossing. Fig. 3 shows the position of the rollers within the cable-tube and the position of the grip. Fig. 25 Fig. 4 is a side view of the grip. Fig. 5 is a plan view of the curve and apparatus. Fig. 6 is a view of the rollers G E and the uniting chain.

A is a line of track, and B is a curve to be 30 turned, or a crossing where another cable-line already laid must be crossed.

C is the cable, which is supported and guided upon pulleys in the usual manner to a point, D, near where the curve commences. At this 35 point the cable is depressed to the bottom of the tube by passing beneath suitable pulleys, and it may be carried around the curve by means of directing-pulleys in any suitable manner.

The device for carrying the car around the curve consists of a chain of rollers, E, which are supported in links F (see Fig. 6) near each end. These rollers travel upon a curved 45 track which runs parallel with the slot through 50 which the shank of the grip passes, and they

are close to the upper part of the tube. This chain is driven by a bevel-gearing, a, which is actuated by the cable C as it passes over the roller at D. Upon the central portion of the rollers E, which lies between the supporting 55 and uniting links, and which is made smaller than the ends, loose sleeves G turn. These sleeves may be stopped in their motion at any time when the rollers from the grip are forced against them without affecting the motion of 60 the rollers E, which travel upon the guide-track. The chain of rollers, after passing the curve, are returned around pulleys H, thus making in effect a continuous endless belt. The grip may be of any of the forms which are 65 used for gripping the cable; but this grip drops the cable just before the latter is depressed at the curve at D, as before described. A secondary apparatus consisting of rollers I, which may be moved up and down in guides 70 on the grip by an independent lever, is employed to engage with the loose sleeves G on the rollers F. These rollers I are moved up until they are crowded against the sleeves or rollers G, when the latter will cease to revolve, 75 and the moving chain of rollers F, traveling upon their tracks, will carry the grip and the car around the curve, after which the rollers I may be depressed, and as the cable also rises to its ordinary position at this point the 80 regular grip may be caused to again engage the cable, and thus continue the movement of the car.

In order to resist the side pressure caused by the crowding of the rollers I of the grip 85 against those G of the moving endless chain, a series of rollers, J, are fixed just outside the plane of the slot in the roadway, so that when the grip-rollers I are forced into contact with the sleeves or rollers G, which lie inside the 90 plane of the slot, this outer line of rollers will press against a rail or plate, K, on the grip, just below the rollers I, and will thus prevent the shank of the grip being forced against the side of the slot. This secondary or resisting 95 set of rollers will be placed upon the outside of the curve and below the line of the rollers I in every case, and a corresponding plate for them to travel upon is fixed to each side of the grip-shank.

The sleeves G are preferably made in a curve from end to end, or conical, and the rollers I are of similar shape, so as to enter between the rollers or sleeves G, and as they are forced up they are crowded or wedged in until they may be moved by the traveling chain of rollers.

When another cable-line is to be crossed it will be manifest that the cable C will be depressed by pulleys in the same manner as before described, so as to pass along the bottom of its tube and below the up-and-down lines of the cable to be crossed. The traveling chains of rollers E will extend from a point near one of the cables to be crossed to the other, or over the space between the two tracks, so that as soon as the grip has been carried across the space occupied by the cable by the momentum of the car the rollers I may be caused to engage the collar G, and thus move 20 the car across the short space between the up-and-down line of the cables of the crossing road.

By the use of this mechanism I am enabled to disengage the grip and stop the car at any 25 point on the curve, which is a convenience upon long gradual curves where it may be desirable.

Having thus described my invention, what I claim as new, and desire to secure by Letters 30 Patent, is—

1. The endless chain of traveling rollers E moving upon guiding rails or tracks near the upper part of the cable-tube, each roller having a sleeve, G, turning upon its axis, in combination with the rollers I upon the grip, and an operating-lever, whereby the rollers may be forced into contact with sleeves or rollers G, so as to be bound or held between them, substantially as and for the purpose herein described. 40

2. The chain of moving rollers G, extending around the curve, so as to be engaged by the grip from the car, in combination with said grip, the fixed rollers J upon the opposite side of the curve, so placed as to press upon and resist side movement of the grip, substantially as herein described. 45

3. The traveling endless chain, consisting of the links F, having the rollers E journaled in them, and the loosely-revolving sleeves G, turning upon them between the links, substantially as and for the purpose herein described. 50

In witness whereof I have hereunto set my hand.

WM. S. RAY.
